UNITED STATES PATENT OFFICE

134,629

DESIGN FOR A BANNER

Leo Y. Booharin, San Francisco, Calif., assignor of one-half to Mark Cooney, San Francisco, Calif.

Application December 24, 1941, Serial No. 104,832

Term of patent 14 years

To all whom it may concern:

Be it known that I, Leo Y. Booharin, a citizen of the United States, residing at 839 Divisadero Street, San Francisco, California, have invented a new, original, and ornamental Design for a Banner, of which the following is a specification, reference being had to the accompanying drawing, forming part thereof.

The figure is a plan view of a banner, showing my new design.

I claim:

The ornamental design for a banner, as shown.
